CLAIM

I claim the ornamental design for a “female coaxial cable connector”, as shown and described.

DESCRIPTION

FIG. 1 is a perspective view of a “female coaxial cable connector” showing my design;

FIG. 2 is a front view thereof (the rear view is the same as the front view);

FIG. 3 is a right side view thereof (the left side view is symmetrical to the right side view);

FIG. 4 is an upper view thereof; and,

FIG. 5 is a bottom view thereof.
